C. H. WILLIAMS,
FOURTH POINT SUPPORT FOR BRAKE BEAMS,
APPLICATION FILED FEB. 27, 1918.

1,304,136.

Patented May 20, 1919.

Inventor
Charles Haines Williams
By *J. W. Cormier, Atty.*

UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

FOURTH-POINT SUPPORT FOR BRAKE-BEAMS.

1,304,136.

Specification of Letters Patent. Patented May 20, 1919.

Application filed February 27, 1918. Serial No. 219,434.

To all whom it may concern:

Be it known that I, CHARLES HAINES WILLIAMS, a citizen of the United States, residing at the city of Chicago, county of Cook, and State of Illinois, have invented a certain new and useful Improvement in Fourth-Point Supports for Brake-Beams, of which the following is a full, clear, and exact description, such as will enable others skilled in the art to which it appertains to make and use the same, reference being had to the accompanying drawings, forming part of this specification, in which—

Figure 1 is a partial top plan view of a diagrammatic form of brake beam showing my improved fourth point support.

Fig. 2 is a side elevational view of said fourth point support.

Fig. 3 is a front elevational view of said support.

Fig. 4 is a plan view of a modified form of support.

This invention relates to a new and useful improvement in fourth point supports for brake beams; the object being to construct the fourth point support so that it can be interchangeable, *i. e.*, used either on the right or lefthand side of the beam, the parts constituting the support and its retaining members being duplicates of each other.

In the drawings, 1 represents a part of the truck to which the supporting track 2 is secured. 3 is the compression member of the brake beam, 4 the tension member, and 5 the brake head. 6 are clips preferably made of rolled, malleablized or wrought metal, where-

by they can be arranged on the tension member on each side of a rocking interchangeable casting 8. As shown in Figs. 1, 2 and 3, this casting 8 is curved laterally and longitudinally so that it will have a rolling point contact with the track support. 40

In Fig. 4, the casting 8^a is shown in dotted lines in its interchangeable position.

It will be readily understood, of course, 45 that still other modifications and adaptations of my improved fourth point support for brake beams may be made without departing from the scope and spirit of what I claim to be my invention. 50

What I claim is:

1. A reversible fourth point support for brake beams loosely arranged upon the tension rod, and having means located on each side thereof for preventing longitudinal 55 movement thereof on said tension rod.

2. A reversible fourth point support for brake beams in the form of a member loosely mounted on the brake beam, and being curved laterally and longitudinally. 60

3. A fourth point support for brake beams comprising a rocking member arranged on a part of the brake beam, and having removable clips on each side thereof for holding said member against longitudinal displacement. 65

In testimony whereof I hereunto affix my signature, this 9th day of February, 1918.

CHARLES HAINES WILLIAMS.

Witnesses:

E. T. WALKER,
M. F. HUNTOON.
